IMPEDANCE MATCHED ANTENNA APPARATUS

Gerald E. Stetson, Buzzards Bay, Mass., assignor to Colonial Aircraft Corporation, Sanford, Maine, a corporation of New York

Application March 20, 1957, Serial No. 647,317

2 Claims. (Cl. 343—864)

The instant invention relates to antenna structure, and in particular, to impedance matched ground plane antenna apparatus designed to achieve efficient operation.

Antenna structure for the VHF communication bands tend to become structurally and electrically complexed to secure efficient standing wave ratio operation, to avoid radiation losses and to achieve over-all system efficiency. Heretofore, economy of manufacture was sacrificed and in addition, highly technical installation personnel were used to install antennas so that optimum antenna operation would be realized.

It is a principal object of the instant invention to provide a ground plane antenna structure that assures efficient standing wave ratio operation for the VHF communication bands, which structure includes an antenna housing adapted to couple the antenna to a load without radiation loss. The housing is also provided with tuning means for maintaining an impedance match over the operating frequency band and by virtue of its novel design permits economy of manufacture, ease of assembly, and installation by inexperienced personnel without sacrificing optimum operation over the desired band width.

It is a further object of the instant invention to provide novel antenna structure in which all conducting elements of the antenna are maintained at the same D.C. potential and all connected directly to the supporting mast. By grounding the mast upon which the antenna is mounted, the entire antenna is protected against lightning without the use of special lightning arrestors thereby providing a safety measure for the protection of operating personnel and equipment.

It is a further object of the instant invention to provide novel antenna structure having a tunable coaxial line transformer and a radiator to coaxial line transition wherein radiation losses are avoided and over-all low standing wave operation of the system is maintained thereby permitting reception of weak signals with usable strength.

It is a further object of the instant invention to provide novel antenna structure wherein an antenna housing is accommodated by a novel arrangement for coupling a tunable transformer thereto to maintain an impedance match thereby assuring efficient standing wave ratio operation.

Other objects and advantages will become apparent upon reading the following description taken in conjunction with the figures, in which:

Fig. 1 is a longitudinal elevation, in section, showing antenna structure incorporating the improvements of the invention;

Fig. 2 is a top plan view of the antenna; and

Fig. 3 is a fragmentary and sectional view of the antenna housing showing certain details thereof.

Referring to the figures, an impedance matched ground plane antenna is made up of a longitudinally extending hollow lower radiator rod 10 and an upper radiator rod 11. Rod 10 is fixed to an antenna housing 12, whereas rod 11 may be slidably adjusted to extend from or re-

tract into rod 10 by a locknut 13 to define an effective $\frac{1}{4}$ wave length vertical radiator. A cylindrically shaped member 14 of insulated material is provided with a large outer diameter upper portion 15 and a smaller outer diameter lower portion 16 longitudinally depending from upper portion 15. Member 14 has a through bore 17 into which base 18 of rod 10 extends coaxially. The upper end of bore 17 is threaded. A mounting nut 19 is provided coaxially mounted over base 18. Nut 19 is provided with a threaded outer surface 20 in register with threaded part of bore 17. Mounting nut 19 has a radial flange 21 bearing against the upper end of member 14. The contiguous surfaces of flange 21 and member 14 are flat to facilitate abutment. Base 18 of rod 10 is provided with spaced apart annular recesses 22, 23. Recesses are juxtaposed flat upper and lower end faces of nut 19. A pair of split-spring-snap-on retainers 24, 25 register within respective recesses and overlap, respectively, the upper and lower surfaces of mounting nut 19 to lock radiator 10, 11 against longitudinal motion.

A cylindrical, hollowed, electrical conducting body 27 encircles smaller diameter part 16 of member 14 and cooperates therewith to define part of the antenna housing 12. Recessed screws 28 hold member 14 and body 27 together.

Bore 17 develops into a relatively large cavity 29 in the intermediate portion of member 14. Conducting body 27 has a transverse through passage 30, the inner end of which communicates with cavity 29. A circular electrically conducting coupling unit 31 provided with a through passage is mounted over the portion of radiator base 18 in the region of cavity 29. Coupling unit 31 is vertically positioned and fastened to base 18 by set screw 32 and cooperates with conducting body 27 to define a coaxial line T junction in cavity 29. A threaded transverse through aperture is provided in unit 31 for set screw 32 to enable the inner end thereof to bite against base 18 of radiator. A lateral through aperture 50 in bodies 16 and 27 provides accessibility to set screw 32 when attaching unit 31 to antenna base 18. Coupling unit 31 also has a transversely extending tubular rod 33 projecting through passage 30 and beyond the outer entrance thereof. An electric conducting hollow outer tube 34 has an opened end held fast to the entrance of passage 30. Tube 34 is suspended coaxially about rod 33.

The terminating ends of rod 33 and tubular body 34, i.e., the ends thereof spaced from housing 12 are provided with an adjustable electrical short to define a coaxial tuning transformer. The transformer is at least $\frac{1}{4}$ wave length at the lowest operating frequency. The short comprises an electrical conducting end plate 35 having an outwardly extending flange 36 slidably engaging the inner bore of tubular body 34, a centrally disposed aperture 37 through which rod 33 extends, and a threaded screw 38 fastened to plate 35 and threaded to one of the pair of anchoring nuts 39 sweated to the inner conductor rod 33 and outer tube 34. A 90° bend 55 in transformer line provides a compact, symmetrical antenna radiator structure for operation over the communication bands. In practice, it has been found that one antenna is capable of covering 30 to 70 mcs. while another scaled antenna will cover 110 to 170 mcs. The tuning transformer matches the antenna to a load over the frequency band of operation.

The lower end of housing 12 is enclosed by a circular electrical conducting terminal block 40 having an upwardly extending circumferential flange 41 projecting over the outer lower surface of conducting body 27. Block 40 is held to body 27 by screws 42. The lower ends of coaxial bodies 27 and 16 nest in the seat created at the upper side of terminal block 40.

The lower end of bore 17 is stepped diametered to receive a tightly fitting washer 43 which cooperates with mounting nut 19 to maintain antenna base 18 in firm coaxial alignment within bore 17. Terminal block 40 has a centrally disposed through passage defined by successive bores 44 and 44a of different diameters. The smaller diametered bore 44 receives a coaxial connector 45 flange fastened to the lower face of terminal block 40 by screws 46. An inner conductor 47 of the coaxial connector 45 is electrically connected to the lower end of fixed rod 10 by a flexible wire 48 extending through bore 44a. Threaded bolt 49 secures wire 48 to rod 10.

Conducting body 27 cooperates with the portion of radiator base 18 extending therethrough to define a coaxial line, which coaxial line terminates in a plane A substantially coplanar with the upper end of cylindrical body 27, to establish a coaxial line to radiator transition. Furthermore, the inner surface of bore 44a and flexible wire 48 may be considered to be a section of coaxial line coupling connector 45 to relatively larger diametered line having body 27 as its outer conductor. The transition will provide smoother electrical characteristics if the diameter of bore 44a is enlarged to a size comparable to the diameter of inner bore surface of body 27, due to the electrical capacities present between body 27 and rod 10 and between terminal block 40 and rod 10, and is so illustrated herein. The coaxial line tuning transformer in effect continues to and terminates at the T junction, consequently, it is seen that there will be no radiator or energy leakage along this line or along the line from plane A to connector 45, which is a continuous coaxial transmission line.

The ground plane reflector may be established by mutually spaced apart radials; four radials electrically approximately $\frac{1}{4}$ wave length long are counterpoised to simulate the ground reflector in the illustrated embodiment. Radials 51 are threaded at inner ends to conducting body 27 and are disposed to lie in a horizontal plane as close to plane A as mechanically convenient.

A mounting adaptor 52 is fastened by bolts 53 to body 27 and covers aperture 50. Adaptor 52 is provided with U bolts 54 designed to engage a standard antenna mast (not shown). Accordingly, all the components of the antenna are at the same D.C. potential and all being connected directly to the supporting mast. Thus by simply assuring that the mast upon which the antenna is mounted has been well grounded, the entire antenna is protected against lightning without the use of special lightning arrestors or other methods. This provides an excellent safety measure for the protection of operating personnel and equipment.

As noted hereinbefore, bend 55 improves the symmetry of the antenna physically, but primarily it is to bring the transformer tuning adjustment screw 38 below the plane of the ground radials 51, thus greatly reducing the capacitive effect of the body of a person making adjustments on the antenna. Being effectively $\frac{1}{4}$ wave length below the ground radials and electrically shielded from the radiator 10, 11, adjustment screw 38 may be approached by installation personnel without seriously disturbing the electrical characteristics of the antenna. Thus, the antenna can be shipped from a factory pretuned, and the user could readily re-tune the system without special equipment or considerations.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. Antenna structure comprising, an adjustable longitudinally extendable and retractable antenna radiator

4

having a lower base portion, an insulated member having a large diametered upper portion and a smaller diametered lower portion depending longitudinally therefrom, said member having a through bore into which said base extends coaxially, an electrical conducting body encircling said smaller diametered part of said member and cooperating therewith to define an antenna housing, means latching said radiator to said housing to lock said radiator against longitudinal motion, said bore developing into a relatively large cavity in the intermediate portion of said member, said body having a transverse through passage, the inner end of said passage communicating with said cavity, radiator reflecting means electrically connected to said body, an electrical conducting coupling unit attached to said base portion of said antenna in the region of said cavity and having a radially extending tubular rod projecting through said passage and beyond the outer entrance thereof, a hollow tubular electrical conducting body having an open end fixed to said passage and being coaxially disposed about said rod, an adjustable electrical short at the ends of said rod and tubular body spaced from said housing and defining an adjustable tuning transformer, an electrical conducting terminal block mounted at the lower end of said housing and having a through aperture aligned with the lower bore end, and connector means mounted at said aperture and enclosing said bore for electrically coupling said radiator to a load.

2. Antenna structure comprising, an adjustable longitudinally extendable and retractable radiator having a lower base portion, an insulated member having a large diametered upper portion and a smaller diametered lower portion depending longitudinally therefrom, said member having a through bore into which said base extends coaxially, the upper end of said bore being threaded, a mounting nut coaxially mounted on said base having spaced apart upper and lower surfaces, said nut having an outer surface threaded to the threaded part of said bore, said base having spaced apart annular recesses, each recess being juxtaposed respective upper and lower surfaces of said nut, split spring retainers registering within said recesses and overlapping said upper and lower nut surfaces to lock said radiator against longitudinal motion, said bore developing into a relatively large cavity in the intermediate portion of said member, an electrical conducting body encircling said smaller diametered part of said member and cooperating therewith to define an antenna housing, said body having a transverse through passage, the inner end of said passage communicating with said cavity, an electrical conducting coupling unit attached to the portion of said base in the region of said cavity and having a radially extending tubular rod projecting through said passage and beyond the outer entrance thereof, an electrical conducting reflecting plane connected to said body, a hollow tubular electrical conducting body having an open end affixed to said passage and being coaxially disposed about said rod, an adjustable electrical short at the terminating ends of said rod and tubular body and defining an adjustable tuning transformer, an electrical conducting terminal block mounted at the lower end of said housing and having a through aperture aligned with the lower bore end, coaxial connector means mounted at said aperture and enclosing said bore, and means connecting the inner conductor of said connector to the lower end of said radiator.
